METHOD OF FIRING STEAM GENERATORS

Martin Frisch, Cranford, N. J., assignor to Foster Wheeler Corporation, New York, N. Y., a corporation of New York

Application November 19, 1936, Serial No. 111,639

9 Claims. (Cl. 122—336)

This invention relates to steam generators and more particularly pertains to methods of firing steam generators and the like.

The invention provides a novel method of firing steam generators and the like which results in complete utilization of the generator furnace volume irrespective of the load on the generator; provides maximum ash deposition in the furnace or furnaces, and attains more complete and more rapid combustion of the fuel employed than has heretofore been attained in the art.

The invention will be understood from the following description when considered in connection with the accompanying drawings forming a part thereof in which:

Fig. 1 is a transverse vertical sectional view of steam generating apparatus arranged for carrying out the method of the present invention;

Fig. 2 is a horizontal sectional view taken substantially on line 2—2 of Fig. 1; and

Fig. 3 is a side elevational view of the apparatus with certain parts in section.

Like characters of reference designate the same or similar parts in the several views.

Although the invention is disclosed in connection with, or as being carried out in, a vertical straight tube type of steam generator having two furnaces flanking the steam generating section of the generator, it will be understood that the invention is capable of being carried out in other types of steam generators and in generators having only a single furnace or having more than two furnaces.

Referring to the drawings, the steam generator illustrated is enclosed in a casing having a front wall 10, a rear wall 11 and side walls 12 and 13. The steam generating section 14 is disposed intermediate two rectangular furnaces 15 and 16. The steam generating section 14 includes a plurality of vertical straight tubes 17 connected into a plurality of square headers 18 and 19, the former being connected by risers 20, headers 21 and risers 22 into a drum 23 which is disposed longitudinally of the steam generating section.

A plurality of downcomers 24 connect the lower portion of drum 23 with the headers 19 and these downcomers are protected from the products of combustion by any suitable refractory material.

The upper portion of drum 23 is connected through a plurality of steam risers 26 with a steam drum 21, from which steam is conducted through a steam pipe 28 to a superheater. In addition to the relatively small tubes 17, the steam generating section includes a plurality of rows of somewhat larger straight vertically

disposed tubes 29. A superheater consisting of a plurality of small loop tubes 30 is disposed at the inlet end of the steam generating section 14. The steam generating section is separated at its sides from the furnaces 15 and 16 by means of the walls 31 and 32 which may be of any suitable form and if desired, may consist of a plurality of armor blocks secured to water wall tubes. Slag screens 33 and 34 are disposed between the forward ends of walls 31 and 32 respectively and the front wall 10 of the boiler casing. All of the walls of the furnaces 15 and 16 are water cooled by water wall tubes 35 and 36 respectively. If desired however, for low capacity installations, the firing wall and the rear wall of each of the furnaces may be installed without water cooling.

In the form of the invention illustrated, the furnaces are fired by a fuel burner 37 disposed in the upper portion of front wall 10 of each furnace and by a burner 38 disposed in the lower portion of the front wall of each furnace. These burners are arranged to discharge jets of fuel and primary air through the spaces between the water wall tubes 35 and 36 and may be of the form disclosed and claimed in my copending application Serial No. 444,906, filed April 17, 1930. Secondary air is supplied to the burners through air ducts 39 which deliver the air to air casings 40 disposed at the outer side of the front wall 10 of each of the furnaces. Secondary air from the casings 40 flows through a plurality of air passages 41 disposed above each of the fuel jets of the burners 37 and 38 and simultaneously through a plurality of air passages 42 disposed below each of the fuel jets of these burners. The volume and velocity of the secondary air discharged through these air passages may be controlled by suitable means such as dampers or the like so that the resulting streams of gases or products of combustion may be directed horizontally through the furnaces or may be inclined either vertically upward or vertically downward. The fuel for combustion, preferably pulverized coal, may be supplied directly from a pulverizing mill 43 to the fuel conduits 44 connected with the burners or may be supplied from a storage system. Other forms of fuel may be utilized if desired, such for example as gas or oil.

The stream of products of combustion from the upper burner 37 in each furnace flows in a horizontal path from the front end of each furnace to the rear end thereof and the stream of products of combustion from the lower burner 38 in each furnace simultaneously flows in a horizon-

tal path from the front end of the furnace through the lower portion thereof to the rear end of the furnace. Adjacent the rear end of each furnace the upper stream turns downwardly and the lower stream turns upwardly and the two streams impinge upon and mix with each other as they turn through an angle of approximately 180°. The resulting stream flows toward the front end of each furnace through the central portion of each furnace intermediate the upper and lower streams. When these resulting streams reach the front end of each furnace, each turns through an angle of 90° in a horizontal plane and passes over the slag screen disposed at the outlet of each furnace and enters the chamber 45 disposed at the forward end of steam generating section 14 and between the furnaces 15 and 16. In this chamber the two streams of products of combustion issuing from the furnaces 15 and 16 impinge upon and mix with each other and thereafter change their direction of flow through another angle of 90° in a horizontal direction and flow over the superheater 30 and pass in a single pass through the steam generating section 14 over the tubes 29 and 17 and pass out through flue 46 at the front end of the steam generating section and flow downwardly therein through the return bend portion 47 and upwardly through the vertically disposed portion 48 into an induced draft fan 49 and thereafter into a stack 50. An economizer may be installed in the return bend section 47 of the flue and an air heater 51 may be employed in the section 48. Air is forced through the air heater by a forced draft fan 52.

With this method of firing, it will be perceived that all, or substantially all, of the furnace volume of each furnace is fully utilized by reason of the fact that streams of products of combustion are continuously flowing through the upper and lower portions of each furnace in the same direction and through the central portion of each furnace in the opposite direction. Additionally, at the point or zone in each furnace where the streams of products of combustion turn to begin their return toward the front end thereof, intensive mixing occurs which results in the speeding up of combustion to a maximum and the reduction of stratification to a minimum. Moreover, it will be perceived that each of the streams of products of combustion is forced to abruptly change its direction of flow twice prior to entering the steam generating section and each of these changes in flow direction is through an angle of approximately 180°, the first turn being in a vertical plane and the second turn in a horizontal plane. With these abrupt changes in flow direction a larger proportion of suspended ash in the streams will be precipitated within the furnace than has been accomplished in the art heretofore.

The method of the present invention may be carried out in apparatus other than the specific form of the steam generator herein disclosed. Additionally, it will be understood that variations may be made in the method and in the several steps thereof without transcending the principles of the invention. For example, a single stream of products of combustion may be produced in each furnace which will flow practically through the entire furnace volume prior to entering the steam generating section, substantially in the manner in which one of the streams flows in the form of the invention disclosed. In this event, there will be no mixing of separate streams in the furnaces, as in the form disclosed. The single stream

of products of combustion will be produced, preferably, by a burner, or tier of burners, so disposed in the lower portion of each furnace that the flame stream or the stream of products of combustion will pass to the rear of the furnace in the lower part thereof, and after turning the stream returns through the central and upper portions of each furnace. Other variations will occur to those skilled in the art. Accordingly, no intention is entertained to limit the invention except by the scope of the appended claims.

What is claimed is:

1. The method of firing a steam generator which comprises producing a plurality of separate, vertically disposed, substantially parallel streams of products of combustion in a furnace, causing said streams to abruptly change their directions of flow in a vertical plane and to impinge upon and mix with each other and to flow through the furnace in a direction substantially parallel to the separate streams, and causing the resulting stream to abruptly change its direction of flow prior to flowing in heat exchange relationship with the steam generating surface of the generator. 25

2. The method of firing a steam generator which comprises producing a plurality of separate, vertically disposed, substantially parallel streams of products of combustion in a furnace, causing said streams to abruptly change their directions of flow in a vertical plane and to impinge upon and mix with each other and to flow through the furnace in a direction substantially parallel to the separate streams, and causing the resulting stream to abruptly change its direction of flow in a substantially horizontal plane prior to flowing in heat exchange relationship with the steam generating surface of the generator. 35

3. The method of firing a steam generator which comprises producing separate streams of products of combustion in the upper and lower portions respectively of a furnace connected with the steam generating section of the generator, causing said streams to flow through the furnace in substantially parallel relationship, causing said streams to abruptly change their directions of flow toward each other and to impinge upon and mix with each other, causing the resulting stream to flow through the furnace between said separate streams in a direction opposite thereto and causing the resulting stream to abruptly change its direction of flow prior to flowing into heat exchange relationship with the steam generating surface of the generator. 50

4. The method of firing a steam generator which comprises producing separate streams of products of combustion in the upper and lower portions respectively of an end portion of a furnace connected with the steam generating section of the generator, causing said streams to flow through the furnace in substantially parallel relationship, causing said streams to abruptly change their directions of flow toward each other and to impinge upon and mix with each other, causing the resulting stream to flow through the furnace between said separate streams in a direction opposite thereto and causing the resulting stream to abruptly change its direction of flow prior to flowing into heat exchange relationship with the steam generating surface of the generator. 65

5. The method of firing a steam generator which comprises producing separate streams of products of combustion in the upper and lower portions respectively of an end portion of a fur- 70

nace connected with the steam generating section of the generator, causing said streams to flow through the furnace in substantially parallel relationship, causing said streams to abruptly change their directions of flow toward each other and to impinge upon and mix with each other, causing the resulting stream to flow through the furnace between said separate streams in a direction opposite thereto and causing the resulting stream to abruptly change its direction of flow in a substantially horizontal plane prior to flowing into heat exchange relationship with the steam generating surface of the generator.

6. The method of firing a steam generator having a steam generating section connected to a plurality of laterally disposed furnaces which comprises producing a stream of products of combustion in each furnace, causing the stream in each furnace to flow successively in opposite directions through different, vertically spaced portions thereof and to abruptly change its direction of flow in its passage therethrough, and causing each stream to abruptly change its direction of flow prior to passing into heat exchange relationship with the steam generating section.

7. The method of firing a steam generator having a steam generating section connected to a plurality of laterally disposed furnaces which comprises producing a stream of products of combustion in each furnace, causing the stream in each furnace to flow successively through different, vertically disposed portions thereof and to abruptly change its direction of flow in its passage therethrough and causing each stream to abruptly change its direction of flow and to impinge upon and mix with the stream from an-

other furnace prior to passing into heat exchange relationship with the steam generating section.

8. The method of firing a steam generator having a steam generating section connected to a plurality of laterally disposed furnaces which comprises producing a stream of products of combustion in each furnace, causing the stream in each furnace to flow successively through different portions thereof and to abruptly change its direction of flow in its passage therethrough, and causing each stream to abruptly change its direction of flow and to impinge upon and mix with the stream from another furnace prior to passing into heat exchange relationship with the steam generating section.

9. The method of firing a steam generator having a steam generating section and a furnace disposed at each side thereof and connected therewith which comprises producing separate streams of products of combustion at one end of each furnace, one stream adjacent the upper portion of each furnace and another stream adjacent the lower portion, causing the streams in each furnace to flow therethrough in substantially parallel relationship, to abruptly change their directions of flow toward each other and to impinge upon and mix with each other, causing the resulting stream in each furnace to flow therethrough between the upper and lower streams and in the opposite direction, causing the resulting stream in each furnace to abruptly change its direction of flow and to impinge upon and mix with the stream from the other furnace and causing said mixed streams to flow in one pass through the steam generating section.
